Filed Mar. 27, 1974, Ser. No. 455,337

Term of patent 14 years

Int. Cl. D9—03

U.S. Cl. D9—219

FIG. 1 is a side elevational view of a storage container for food or the like showing my new design, the other three sides being the same in appearance;

FIG. 2 is a top plan view;

FIG. 3 is a bottom plan view with a portion being broken away for convenience of illustration;

FIG. 4 is an enlarged fragmentary section view taken on the line 4—4 of FIG. 1; and

FIG. 5 is a cross-sectional view through the cover portion taken on the line 5—5 of FIG. 2.

I claim:

The ornamental design for a storage container for food or the like, as shown and described.
